UNITED STATES PATENT OFFICE.

FREDERIC C. HUTT AND THOMAS S. STAFFORD, OF KENNETH, INDIANA,
ASSIGNORS OF ONE-THIRD TO MARGARET GREENBANK, OF SAME PLACE.

WRENCH.

SPECIFICATION forming part of Letters Patent No. 653,476, dated July 10, 1900.

Application filed April 14, 1900. Serial No. 12,795. (No model.)

To all whom it may concern:

Be it known that we, FREDERIC C. HUTT and THOMAS S. STAFFORD, citizens of the United States, residing at Kenneth, in the county of 5 Cass and State of Indiana, have invented certain new and useful Improvements in Wrenches; and we do declare the following to be a full, clear, and exact description of the invention, such as will enable others skilled 10 in the art to which it appertains to make and use the same, reference being had to the accompanying drawings, and to the letters of reference marked thereon, which form a part of this specification.

15 Our invention relates to a socket-wrench of the reversible type, and has reference more particularly to the class of wrenches which are especially adapted for use in manipulating the nuts on railway-track bolts, 20 one object being to provide a cheap and durable wrench which shall possess advantages of a ratchet-wrench and also be capable of instantaneous reversal, so that a nut may be worked back and forth on its bolt in cases 25 when one fits too tightly upon the other.

Another object is to provide a wrench in which the part which usually wears out first may be cheaply replaced by a new part without special fitting, thus saving the more expensive part.

The invention consists of a socket-head and a lever and lever-head of new and novel form of construction; and it consists, further, in the parts and combination and arrangement of parts hereinafter particularly described and claimed.

Referring to the drawings, Figure 1 represents our complete wrench in a central longitudinal vertical sectional view; Fig. 2, a 40 plan view of the top of the socket-head, on a reduced scale; Fig. 3, a bottom plan view of the complete wrench; Fig. 4, an elevation or side view of the axial bolt; Fig. 5, a fragmentary view of the upper side of the lever, 45 showing the finger-lever; Fig. 6, an elevation view of the socket-head; Fig. 7, a fragmentary top plan view of the lever-head, and Fig. 8 a front elevation of the lever-head.

Similar letters of reference in the several 50 figures of the drawings designate similar parts.

In construction we provide a circular socket-head A, in the smaller end *r* of which is a nut-socket *a*, which may be formed suitably either for engaging a hexagonal nut or 55 for a square nut. The wall of the socket has a conical periphery *s*, extending somewhat over half the length of the head, the balance being cylindrical, and the opposite end has a plane surface *d*. Extending from the socket *a* is a smaller socket *b*, designed to receive the bolt end which may project through a nut. A circular journal-aperture C extends from the socket *b* to the face *d*. In the cylindrical periphery *t* is an annular guide-groove D, and between this and the upper 60 end is an annular groove *e*, in which is a series of sockets E, disposed radially from the center of the head, the groove *e* being designed to afford a smooth protected surface 70 which shall not be liable to become battered by contact with other tools or hard substances, as wrenches are exposed to in practice, and being protected by the periphery *t* the orifices of the sockets E are prevented 75 from becoming defaced at the edges.

The axial bolt F has a head *m* operating against the bottom of the socket *b*, and adjacent to the head is a journal portion *n*, which is fitted revolvably in the aperture C, 80 a smaller portion *p* having screw-threads *q*, to which is fitted a suitable screw-nut G, preferably having an extended cap serving as a handle for guiding the wrench. A shoulder *v* provides a bearing against which the 85 nut may draw without binding the socket-head against the bolt-head *m*.

The lever H includes a part *f*, continuing at a right angle to the main part of the lever, and a continuing part *h*, thus offset and in a 90 line parallel to the main part, which together form the lever-head. The part *h* has a bolt-hole N, which receives the part *p* of the bolt F, the shoulder *v* bearing against the under surface *u* of the part *h*, the surfaces *d* and *u* 95 sliding against each other as the bolt rotates in the head A. The part *f* forms a housing in which is a guideway O, preferably circular, having a sliding latch-bolt J fitted therein and in register with the sockets E, which the 100 end of the bolt is adapted to enter. Below the bolt J is a tongue I, engaging the groove

D, providing bearings whereby the lever-head is reinforced, and thereby obviating the necessity of employing disproportionately-heavy and more expensive parts. The free end of 5 the lever H has a finger-lever K, having ears l connected thereto by a pintle i, and is normally held off by a spring M, secured to the lever by a rivet k. A rod L is connected at one end to the lever K by a pintle j and at its 10 opposite end is connected to the bolt J by a pintle w, so that the bolt may be forced into the sockets E by the spring M and may be withdrawn by pressing the finger-lever toward the main-lever handle.

15 It is pointed out that all parts may either be rough-forged or cast from steel and be fitted together with very little labor, such as dressing down rough edges, and therefore may be produced inexpensively, as is desirable in 20 wrenches of this type, and the attainment of these advantages is of great value.

The practical use of this invention will be understood from the foregoing description in detail; but it may be mentioned that in applying 25 the socket-head to a nut one hand may grasp the nut G, while the lever H is held in the other hand, so that the socket may be quickly fitted to the nut, and by allowing the bolt J to remain in a socket E the nut may be 30 worked to and fro, as with an ordinary wrench, and by manipulating the finger-lever K the wrench may be used as a ratchet-wrench, instantaneously reversing it, as may be desired.

Having thus described our invention, what 35 we claim, and desire to secure by Letters Patent, is—

1. A wrench provided with a socket-head having an annular groove in the periphery thereof and sockets in the bottom of the

groove, a lever pivoted to the socket-head, 40 and a bolt mounted in the head and registering with the sockets.

2. A wrench including a socket-head having an annular groove in the periphery thereof having sockets therein, a main lever pivoted 45 to the socket-head and having a latch-bolt slidingly mounted therein in register with the sockets, a finger-lever pivoted to the main lever, and a rod connected to the finger-lever and also to the latch-bolt. 50

3. A wrench including a socket-head having an annular groove and sockets therein, a main lever pivoted to the socket-head and having a latch-bolt slidingly mounted therein in register with the sockets, finger-lever pivoted to the main lever, a rod connected to the finger-lever and also to the latch-bolt, and a tongue and a groove working in connection 55 whereby the lever-head is reinforced.

4. In a wrench, the combination of the 60 socket-head, the lever-head, the lever formed integral with the lever-head, the axial bolt secured in the lever-head and working in the socket-head, the annular groove in the socket-head having the sockets therein, the annular 65 guide-groove in the socket-head, the finger-lever, the finger-lever spring, the latch-bolt, the rod connecting the latch-bolt with the finger-lever, and the tongue attached to the lever-head and engaging the guide-groove, substantially as set forth. 70

In testimony whereof we affix our signatures in presence of two witnesses.

FREDERIC C. HUTT.
THOMAS S. STAFFORD.
